UNITED STATES PATENT OFFICE.

OTTO JOSEPH BARON BOESELAGER, OF MOUNT ANGEL, OREGON.

PROPELLER FOR VESSELS.

SPECIFICATION forming part of Letters Patent No. 449,996, dated April 7, 1891.

Application filed May 28, 1890. Serial No. 353,513. (No model.)

To all whom it may concern:

Be it known that I, OTTO JOSEPH BARON BOESELAGER, a subject of the Emperor of Germany, residing at Mount Angel, Marion county, and State of Oregon, have invented a new and useful Improvement in Propeller Vessels Employing Steam as a Motive Power, of which the following is a specification, reference being had to the accompanying drawings, forming a part thereof.

The object of my invention is to substitute for the screw-propellers of vessels paddles operated by suitable mechanism in such manner as to give them a movement similar to sculling or paddling, so that the vessel may receive its impulsion directly from the combined repulsive force exerted by the water and the paddles against each other, thereby attaining greater power and speed, and, as will appear, the vessel is at the same time placed under more complete control for the purpose of stopping, turning, and reversing or backing. This object I accomplish in the manner illustrated in the accompanying drawings, in which—

Figure 1 is a horizontal section through the keel-frame of a vessel just above the paddles and the mechanism which connects the paddles with the power-driven shafts, showing the relative arrangement of the alternate paddles and their connecting mechanism when the paddles are at the extreme limit of their movement in one direction. Fig. 2 is a side elevation of a portion of the keel-frame, a paddle, the vertical power-driven shafts, and the connections between the paddle and the said shafts. Fig. 3 is a horizontal section of a portion of the keel-frame, showing the paddle at the extreme limit of its movement in one direction, its position being reversed to that shown in Fig. 1 prior to the stroke in the opposite direction. Fig. 4 is a horizontal section of the vertical power-driven shafts taken above the connections with the motive power. Fig. 5 is a detail section showing the manner of connecting the arms with the power-driven shaft.

In the keel-frame K, located in the stern of the vessel, are supported the vertical shafts D E. The shafts D are provided at different relative levels with two horizontal arms B and B', between which are suspended about

midway of their ends on pivots a the paddles A. Shafts D have also two cross-arms H H' at different relative levels, working in an annular groove therein, as seen in Fig. 5; and shafts E have two cross-arms I I' corresponding in position with the cross-arms H H', rigidly secured thereto. The cross-arms H and I are connected at their ends by means of the links L L and the cross-arms H' and I' are connected at their ends by corresponding links L L. The paddles are provided with cross-arms J and M on their opposite edges in line with the pivots a, which arms are connected with the ends of the cross-arms H and H' by means of the links C and C', respectively. The cross-arms J M H H' I I' are of equal length and the links C C' and the arms B B' are of equal length and arranged in parallel position.

The cross-arms and the links constitute the stopping or regulating mechanism governing the reciprocating motion or stroke of the paddles. From the sides of the shafts D E extend the lever-arms b c, respectively, which are connected by means of the links g f and rods F G with any suitable operating power or machinery not shown.

The movement of the paddles is shown in Fig. 1, paddles A A being seen in their extreme point of outward stroke and paddles A' A' in their extreme point of return-stroke. Supposing that the paddles A A are to be started on their return-stroke, the operating power is transmitted through the lever-arms b c and links L L' C C' to the cross-arms J M on the paddles throwing the same at the angle shown in Fig. 3, in which movement the operating power is largely aided by the repulsive force exerted by the water, as indicated by the arrow in Fig. 3. Having attained this position the paddles are ready to be started by the arms B B' on their return-stroke, the links C C' L L' and cross-arms H H' I I' retaining them in the acute angle which they have assumed until they have reached their extreme point of return-stroke and the same movements are accomplished by the paddles in the course of their sweep or stroke in the opposite direction.

As is obvious, powerful engines must be used to supply the motive power; and it is necessary that the alternate paddle move-

ments A A and A' A' be coupled together and operated by independent motive power, so that the first and third paddles will reciprocate the motion of the second and fourth, imparting an even impelling force urging the vessel forward, or, by reversing this movement, converting the same into a repelling force urging the vessel backward. By stopping one or more of the paddles at their extreme outer or inner point of stroke the same will be converted into a rudder, enabling the vessel to be steered thereby or turned about in a very short space, and stopping two paddles at their extreme inner point of stroke and the remaining two paddles at their extreme outer point of stroke will cause the vessel to be stopped almost instantly.

Having thus described my invention, what I claim, and desire to secure by Letters Patent, is—

The hereinbefore-described mechanism for propelling, steering, and stopping vessels, consisting of the vertical shaft B, having the arms B and B' rigidly connected therewith, the paddle pivoted between the arms B and B',²⁵ the cross-arms J and M rigidly connected with the paddle in line with its pivotal connection with the arms B and B', the cross-arms H and H' loosely mounted on shaft D, the links C and C' connecting the ends of the cross-arms H and H' with the ends of the cross-arms J and M, and means for independently operating shaft D and the cross-arms H and H', substantially as set forth, for the purpose described.³⁰

OTTO JOSEPH BARON BOESELAGER.
